BATHING CAP

Clyde Maurice Moore, Richmond, Va.

Application June 2, 1948, Serial No. 30,529

19 Claims. (Cl. 2-68)

1

This invention relates to caps or head coverings and more particularly to beach bathing cap constructions suitable to be used for swimming or other bathing purposes.

This application is a continuation-in-part of my copending application for Bathing Cap, Serial No. 740,583, filed April 10, 1947, and one of the primary objects of this invention is to provide improved forms of face and neck sealing bands for use in connection with the various bathing caps disclosed in said copending application, particularly with respect to the manner of splitting or dividing the face and neck sealing band and the means for connecting the end portions thereof together to provide a face sealing band portion adapted to extend down each side of the face and under the chin of the wearer, and a neck sealing band portion adapted to extend around the neck of the wearer. It is therefore desired to incorporate in this application all of the subject matter disclosed in my said copending application.

Another primary object of the invention is to provide a bathing cap including a head covering provided with a fullness to receive and loosely engage certain portions of the hair of the wearer.

Another object of the invention is to provide a bathing cap which will effectively and efficiently prevent ingress of water to the hair of the wearer.

A further object of the invention is to provide a face and neck sealing band structure of elastic material which will conform to the contour of the skin, and which may be attached to a head covering of water-proof material to prevent ingress of water to the hair of the wearer.

An additional object of the invention is to provide a face and neck sealing band of the aforementioned type in which the band is split or divided, and means are provided for connecting and disconnecting the margins of the split.

Another object of the invention is to provide a bathing cap construction comprising a face and neck sealing band of elastic material and a head covering connected thereto, said head covering being constructed of a water-proof material.

A further object of the invention is to provide a bathing cap construction comprising a face and neck sealing band of elastic material, and a head covering of water-proof material connected thereto, in which the band is split or divided to provide free end portions and means are provided for connecting such end portions in overlapping relationship.

A still further object of the invention is to pro-

2

vide a bathing cap construction comprising a face and neck sealing band of elastic material, and a head covering of water-proof material connected thereto, in which the band is split or divided to provide free end portions, and adjustable means are provided for connecting such end portions in overlapping relationship.

A further object of the invention is to provide a bathing cap construction comprising face and neck sealing marginal portions of highly elastic material and a head covering having less elasticity than said marginal portions.

An additional object of the invention is to provide a bathing cap of unitary elastic construction having marginal portions adapted to extend around the face and neck of the wearer, in which the marginal portions are molded in a constricted manner to insure a tighter fit around said marginal portions than throughout the other portion of said cap.

A further object of the invention is to provide a bathing cap of unitary construction comprising highly elastic material throughout and including portions adapted to extend around the face and neck of the wearer.

An additional object of the invention is to provide a bathing cap construction comprising a head covering of water-proof material and a sealing band of elastic material adapted to extend down each side of the face, under the chin and around the neck of the wearer.

Other objects and advantages of the invention will become apparent as the description proceeds, reference being had to the accompanying drawings, wherein:

Fig. 1 is a side view showing one form of cap embodying features of the invention applied to the head with the band tensioned and the end portions thereof in open position to illustrate the fastening means;

Fig. 2 is a side view similar to Fig. 1, but illustrating the end portions of the band connected together in overlapping relationship;

Fig. 3 is a side view similar to Fig. 2 of the opposite side of the cap;

Fig. 4 is an enlarged fragmentary sectional view of the band taken along the line 4-4 of Fig. 2, looking in the direction of the arrows.

Fig. 5 is a side view similar to Fig. 1, illustrating the manner in which the cap fits the head of the wearer before the band is tensioned;

Fig. 6 is a side view of a modified form of my bathing cap applied to the head illustrating the manner in which the cap fits the head before the band is tensioned;

Fig. 7 is a side view similar to Fig. 6 illustrating the manner in which the modified form of cap fits the head when in use, with the band tensioned;

Fig. 8 is an opposite side view of Fig. 7;

Fig. 9 is a top view of the cap illustrated in Figs. 6, 7 and 8;

Fig. 10 is a fragmentary sectional view taken along the line 10—10 of Fig. 9 looking in the direction of the arrows;

Fig. 11 is a fragmentary sectional view taken along the line 11—11 of Fig. 10 looking in the direction of the arrows; and

Fig. 12 is a perspective view of a still further modified form of my bathing cap.

Referring to Figs. 1 to 5 of the drawings in detail, the bathing cap generally indicated by the reference numeral 1 comprises a relatively thin face and neck sealing band, generally indicated by the numeral 2, which is preferably made of a highly elastic, moldable material such as rubber.

The face and neck sealing band 2 comprises a face sealing band portion 3, and a neck sealing band portion 4. The face sealing band portion 3 is preferably of a generally circular, oval, or heart shape and is adapted to extend in a continuous manner across the forehead, down each side of the face, and under the chin of the wearer, and the neck sealing band portion 4 of the band 2 is adapted to extend around the neck of the wearer.

The preferred method of making the face and neck sealing band 2 is to mold the same as a unitary structure, substantially as illustrated in Figs. 1 to 3.

The peripheral length of the generally circular, oval, or heart shaped face band portion 3, and the length of the neck band portion 4, are preferably such that considerable stretching or tensioning of the highly elastic material in the band is maintained when in position on the face and neck of the wearer. This stretching or tensioning is desirable in order to maintain an absolutely effective seal and generally, an increase in the lengths of the band portions 3 and 4 of approximately 50% provides a highly effective seal without interfering with the comfort of the wearer. The value of 50% is given as an illustration, not as a limitation, since obviously the increase in the said lengths may vary widely. The specific said increase will depend to some extent upon the elasticity of the particular material used, and also, upon the personal likes and dislikes of the wearer. Further, the specific use of the cap will be a factor, e. g., shower bathing does not require the seal to be as effective as does beach bathing.

The face sealing band portion 3 and the neck sealing band portion 4 are each provided with a substantially circular stiffening and sealing projection or bead 5 along the free edge thereof to aid in providing an effective seal.

The drawings clearly illustrate the manner in which the band 2 is split or divided, and the portion 7 of the band passes under the chin, the upper half thereof may be considered to be a portion of the face band 3, and the lower half thereof may be considered to be a portion of the neck band 4. The total width of the portion 7 of the band 2, however, is preferably less than the combined widths of the remainder of the face and neck band portions 3, 4.

Preferably, the portions 7 of the band 2 is made thicker than the other portions thereof to resist or prevent folding due to movement of the chin of the wearer, and at one end portion thereof, the

portion 7 of the band merges into and integrally connects with the band portions 3 and 4 at the juncture 8 thereof at one side of the bathing cap. The other end of the portion 7 of the band is provided with an extension 9, preferably, but not necessarily, bifurcated, comprising an extension 3' of the face band portion 3 and an extension 4' of the neck band portion 4. The normally free end portion 9 of the band 2 is adapted to overlap a second normally free end portion 10 of the band formed at the juncture of the band portions 3 and 4 at the opposite side of the bathing cap, with the extensions 3' and 4' overlapping the band portions 3 and 4, respectively.

15 The end portions 9 and 10 of the band 2 are provided with preferably a plurality of spaced snap fastening means 11 comprising elements 12 secured to extensions 3' and 4' and cooperating elements 13 secured to band portions 3 and 4. 20 The spaced fastening means 11 provide means whereby the band portions may be adjusted to different wearers of the cap, or whereby said band portions may be adjusted to different degrees of tension by the same wearer.

25 The face and neck sealing band 2 is suitably secured to a head covering 14 which is made of a water-proof material. The head covering 14 forms the main body portion of the cap 1 and, as illustrated, is of one-piece construction, although it may be made of several pieces as will be later described in connection with the modifications, if desired, and the pieces secured together in any suitable manner to render the construction waterproof, as by vulcanizing.

30 The head covering 14 may be constructed of an elastic material having less elasticity than the band 2, may be substantially non-elastic, or the degree of elasticity of the head covering 14 may equal that of the face and neck sealing band 2 and thus, if desired, the head covering 14 may be constructed of the same material as the band 2 and may be integrally connected therewith, thereby providing a cap 1 of unitary construction. Alternatively, the head covering 14 may be constructed of the same elastic material as the band 2 but rendered less elastic than the band by reinforcement, as by being made thicker than the band 2. Other suitable materials for the head covering 14 are rubberized silk, nylon, or other woven fabric material, or rubber having a smaller degree of elasticity than the band 2. When the latter materials are used, the band 2 is suitably secured to the head covering 14, as by overlapping and vulcanizing.

35 In placing the cap 1 on the head, the wearer places the cap on the head in the usual manner. Fig. 5 illustrates the more or less wrinkled condition of the head covering at this point before the band is tensioned. Then, grasping the end portions 9 and 10 of the band 2, the wearer stretches or tensions the face and neck sealing band portions 3 and 4, overlaps the end 10 with the end 9, and fastens two or more of the separable fastening means 12. The degree of wrinkling of the head covering portion may, of course, be reduced or eliminated by making the marginal portion or outer edge only of the face and neck bands of a length less than that of the rest of the band when in unstretched condition, as is well known in the art. Such a construction limits most, or all, of the stretching to the marginal portion of the band when the cap is fastened in place.

40 The modified forms of cap illustrated in Figs. 6 to 11 and Fig. 12 differ from the form previ-

ously described substantially only with respect to the manner in which the band is split or divided, and in the construction of the head covering in that a fullness is provided therein to receive and loosely engage certain portions of the hair of the wearer.

In these forms of the invention, as before, the bathing caps, generally indicated by reference numerals 101 and 201, respectively, comprise a relatively thin face and neck sealing band, generally indicated by the numeral 102, which is preferably made of a highly elastic, moldable material such as rubber.

The face and neck sealing band 102 comprises a face sealing band portion 103, and a neck sealing band portion 104, each of which is provided with a substantially circular stiffening and sealing projection or bead 105 along the free edge thereof to aid in providing an effective seal.

The band portions 103 and 104 of the band 102 have, as do the band portions 3 and 4 of the band 2, a length, or effective sealing length, normally less than that required to surround the face and extend around the neck, respectively, of the wearer; the face sealing band portion 103 is adapted to extend in a continuous manner across the forehead, down each side of the face, and under the chin of the wearer, and the neck sealing band portion 104 of the band 102 is adapted to extend around the neck of the wearer.

The band portion 102 is split or divided in such a manner, as clearly illustrated, that two separate, preferably thicker, free end portions 106 and 107 pass under the chin of the wearer. The band portion 106 forms a part of the face sealing band portion 103, is integrally connected thereto at one side of the cap at the juncture 108 of the band portions 103 and 104, and is adapted to overlap the lower portion 109 of the band portion 103 at the other side of the cap. The band portion 107 forms a part of the neck sealing band portion 104, is integrally connected thereto at the side of the cap opposite the juncture 108 at the juncture 110 of the band portions 103 and 104, and is adapted to overlap the forward portion of the band portion 104 adjacent the juncture 108.

The free end portions 106 and 107 of the band 102 are provided with a plurality of spaced snap fastening means 111 comprising elements 112 secured to the band portions 106 and 107 and cooperating elements 113 secured to the band portions 103 and 104. The spaced fastening means 111 provide adjustability in the tensioning of the band as previously described.

In the form of the invention illustrated, the band portion 106 overlies the band portion 107 in use, and preferably, but not necessarily, beads 105' are provided at the junctures 108 and 110 of the band portions 103 and 104. The beads 105' extend from the bead 105 of the face band portion to the bead 105 of the neck band portion.

Referring now to the bathing cap 101 disclosed in Figs. 6 to 11, the face and neck sealing band 102 is suitably secured to a head covering 114 which is made of a water-proof material. The head covering 114 forms the main body portion of the cap 101 and, in the form illustrated, is of three piece construction, although more or less pieces may be used, and comprises two side portions or panels 114' and a central portion or panel 114'' secured together at the seams 115 (Fig. 11) in any suitable manner to render the construction waterproof, as by vulcanizing.

The head covering 114 may be constructed of

an elastic material having preferably less elasticity than the band 102, or it may be substantially non-elastic. Thus, for example, the head covering 114 may be made of rubberized silk, nylon, or other woven fabric material, or rubber, and the band 102 may be suitably secured to the head covering 114 by overlapping and vulcanizing as indicated at 116, Fig. 10.

In order to provide the cap 101 with a fullness, to receive and loosely engage, or to make room for, certain more or less bulky portions of the hair of the wearer; such as knots, up-sweep hair-do, and the like, the central portion or panel 114'' of the head covering 114 is made full or provided with a fullness comprising a plurality of folds, pleats or gathers.

In the form illustrated, the top or forward portion 119 of the panel 114'' is provided with a plurality of longitudinally extending folds 120, and the rearward or back portion 121 of the panel 114'' is provided with a plurality of transversely extending folds 122. It will be obvious, of course, that longitudinally extending folds may be substituted for the transversely extending folds, and vice versa, if desired. It may be here pointed out that when longitudinally extending folds only are provided, the head covering is preferably of one piece construction.

Approximately midway longitudinally of the central portion or panel 114'', a reinforcing band 123 is connected to the seams 117 at its ends as by stitching 124. The band 123 thus connects and co-acts with the side portions or panels 114' to assure proper positioning of the band 102 relative to the face and neck under tension.

The band 123 may be made of non-elastic material, if desired, but preferably, it is made of a material having relatively low elasticity to render the same adjustable and thus make the cap 30 adjustable to heads of different sizes.

Fig. 6 illustrates the cap 101 in position on the head of the wearer before the band 102 is tensioned. It will be noted that in this position the folds 120 and 122 have not opened appreciably. Figs. 7 and 8 illustrate the cap after the band has been tensioned and the band portions 106 and 107 secured, and it will be noted that in this instance, bulky portions of the hair of the wearer have caused both the folds 120 and 122 to open.

This construction obviously adds greatly to the comfort of the wearer, since bulky portions of the hair are not pressed tightly against the head of the wearer, and in addition there is less disarrangement of the hair than with conventional or tight fitting bathing caps.

The further modified form of bathing cap 201 illustrated in Fig. 12 is also provided with a fullness, for the reasons previously pointed out, and comprises a head covering 214 secured to the face and neck sealing band 102 as previously described.

The head covering 214 may be made of the same materials as the covering 114, and comprises two side panels 214' and a central panel 214'' secured together as previously described. The top or forward portion 219 of the central panel 214'' is of a width to co-act with the side panels 214' to maintain the band 102 properly positioned relative to the face and neck under tension, and the rearward or back portion 221 of panel 214'' is cut outwardly on a bias, is relatively wider than the forward portion, and in addition is relatively long so as to form a fullness or snood 224 adapted to depend below the neck band portion 104 of the band 102.

Obviously, if desired, the cap 201 may be con-

structed to include folds such as the folds 120 or 122 at the forward portion 219 of the central panel 214" if a reinforcing band such as the band 123 is provided.

It will also be obvious that the head covering 14 may be used with the band 102, the head coverings 114 or 214 may be used with the band 2, if desired, and as stated above, any of the several forms of bathing cap disclosed in my copending application Serial No. 740,583 may be modified relative to the band or head covering constructions in the manner disclosed herein. Thus, in addition to the modified forms above referred to herein which are disclosed in my said copending application, the band portion 3 or 103 may be omitted across the forehead of the wearer, or the band portions 3 and 4, or 103 and 104 may be made more resilient than the head covering without such difference being defined by a visible band, as when the band is rendered more resilient or elastic than the head covering by compounding or by blending two different types of material, e. g., by the coagulation dip or similar methods well known to the rubber industry.

It is to be noted that all of my bathing caps may be considered to comprise a head covering of water-proof material having a face receiving aperture and a neck receiving aperture and adapted to completely house the hair and ears of the wearer, in which the neck and face receiving apertures such as 15 and 16, respectively, of Figs. 2 and 3 for examples, are provided marginally thereof with the property of high elasticity.

While the invention is susceptible of various modifications and alternative constructions, I have herein disclosed in detail the preferred embodiments, but it is to be understood that I do not thereby intend to limit the invention to the specific forms disclosed, but intend to cover all modifications and alternative constructions falling within the spirit and scope of the invention as expressed in the appended claims.

My copending application Serial No. 740,583, hereinabove referred to is a continuation-in-part of my application Serial No. 674,170, filed June 4, 1946, now abandoned.

I claim:

1. A substantially water-proof bathing cap construction comprising, in combination, a face and neck sealing band of highly elastic water-proof material, said band comprising a face sealing band portion adapted to extend in a continuous manner across the forehead, down each side of the face and under the chin of the wearer, and a neck sealing band portion adapted to extend around the neck of the wearer; a substantially water-proof head covering secured to said face and neck band, said head covering having less elasticity than said face and neck sealing band; said band being divided and having end portions adapted to overlap each other along a considerable length of said face sealing band portion and also along a considerable length of said neck sealing band portion; and means for connecting said end portions together in such overlapping relationship.

2. A substantially water-proof bathing cap construction comprising, in combination, a face and neck sealing band of highly elastic water-proof material, said band comprising a face sealing band portion adapted to extend in a continuous manner down each side of the face and under the chin of the wearer, and a neck sealing band portion adapted to extend around the neck of the wearer; a substantially water-proof head cover-

ing secured to said face and neck band, said head covering having less elasticity than said face and neck sealing band; said band being divided and having end portions adapted to overlap each other; and means for connecting said end portions together in such overlapping relationship.

3. For use in a substantially water-proof bathing cap construction, a face and neck sealing band of highly elastic water-proof material, said band comprising a face sealing band portion adapted to extend in a continuous manner across the forehead, down each side of the face and under the chin of the wearer, and a neck sealing band portion adapted to extend around the neck of the wearer; said band being divided and having end portions adapted to overlap each other, and means for connecting said end portions of said band together in overlapping relationship, one of said end portions being bifurcated and so shaped that one terminal branch thereof forms a portion of said face sealing band while the other terminal branch forms a portion of said neck sealing band when the said end portions are secured in overlapping relationship.

4. A substantially water-proof bathing cap construction comprising a substantially water-proof head covering and a face and neck sealing band of highly extensible water-proof material, said band comprising a face sealing band portion adapted to extend in a continuous manner across the forehead, down each side of the face and under the chin of the wearer, and a neck sealing band portion adapted to extend around the neck of the wearer, the said face and neck sealing band portions each having a length normally less than that required to surround the face and extend around the neck, respectively, of the wearer; whereby considerable stretching or tensioning of the highly extensible material in the band is maintained when in position surrounding the face and extending around the neck of the wearer; said band being divided and having end portions adapted to overlap each other along a considerable length of said face sealing band portion and also along a considerable length of said neck sealing band portion, and means for connecting said end portions of said band together in such overlapping relationship.

5. For use in a substantially water-proof bathing cap construction, a face and neck sealing band of highly extensible, water-proof material, said band comprising a face sealing band portion adapted to extend in a continuous manner down each side of the face and under the chin of the wearer, and a neck sealing band portion adapted to extend around the neck of the wearer, the said face and neck sealing band portions each having a length normally less than that required to substantially surround the face and extend around the neck, respectively, of the wearer; whereby considerable stretching or tensioning of the highly extensible material in the band is maintained when in position substantially surrounding the face and extending around the neck of the wearer; said band being divided and having end portions adapted to overlap each other along a considerable part of said face sealing band portion and also along a considerable part of said neck sealing band portion, and means for connecting said end portions of said band together in such overlapping relationship.

6. A bathing cap comprising a head covering provided with a face receiving aperture and a neck receiving aperture, said head covering comprising water-proof material adapted to com-

pletely house the hair and ears of the wearer and to extend about the neck, under the chin, and upwardly along the face and across the forehead of the wearer, said water-proof material being provided at the margins of the neck receiving aperture and the face receiving aperture with the property of high elasticity, said margins defining a face sealing band portion and a neck sealing band portion adapted to be maintained under tension during use, whereby to effect a positive fluid seal between said margins and the body of the wearer; said margins being divided in the vicinity common to both of said face and neck sealing band portions and having end portions adapted to overlap each other, one of said end portions being bifurcated to form a pair of terminal branches each having fastening means thereon, one of said terminal branches being adapted to overlie and be secured to coacting fastening means on said face sealing band portion and the other of said terminal branches being adapted to overlie and be secured to coacting fastening means on said neck sealing band portion.

7. A substantially water-proof bathing cap construction comprising, in combination, a face and neck sealing band of highly elastic water-proof material, said band comprising a face sealing band portion adapted to extend in a continuous manner across the forehead, down each side of the face and under the chin of the wearer, and a neck sealing band portion adapted to extend around the neck of the wearer; a substantially water-proof head covering secured to said face and neck band, said head covering having less elasticity than said face and neck sealing band and being provided with a fullness to compensate for the lesser elasticity thereof; said band being divided and having end portions adapted to overlap each other; and means for connecting said end portions together in overlapping relationship.

8. A substantially water-proof bathing cap construction comprising, in combination, a face and neck sealing band of highly elastic water-proof material, said band comprising a face sealing band portion adapted to extend in a continuous manner down each side of the face and under the chin of the wearer, and a neck sealing band portion adapted to extend around the neck of the wearer; a substantially water-proof head covering secured to said face and neck band, said head covering having less elasticity than said face and neck sealing band and being provided with a fullness to compensate for the lesser elasticity thereof; said band being divided and having end portions adapted to overlap each other; and means for connecting said end portions together in overlapping relationship.

9. A substantially water-proof bathing cap construction comprising a substantially water-proof head covering having a fullness provided by material in excess of a minimum amount required to cover the head of a wearer and including face and neck sealing marginal portions of highly extensible material, said marginal portions comprising a face sealing portion adapted to extend in a continuous manner across the forehead, down each side of the face and under the chin of the wearer, and a neck sealing portion adapted to extend around the neck of the wearer, the said face and neck sealing portions each having a length normally less than that required to surround the face and extend around the neck, respectively, of the wearer; whereby considerable stretching or tensioning of said highly extensible

material is maintained when in position surrounding the face and extending around the neck of the wearer.

10. A substantially water-proof bathing cap construction comprising a substantially water-proof head covering portion and face and neck sealing marginal portions of highly extensible material said head covering portion having a plurality of folds to provide a fullness therein, said marginal portions comprising a face sealing portion adapted to extend in a continuous manner across the forehead, down each side of the face and under the chin of the wearer, and a neck sealing portion adapted to extend around the neck of the wearer, the said face and neck sealing portions each having a length normally less than that required to surround the face and extend around the neck, respectively, of the wearer; whereby considerable stretching or tensioning of said highly extensible material is maintained when in position surrounding the face and extending around the neck of the wearer.

11. A substantially water-proof bathing cap construction comprising a substantially water-proof head covering including side and central portions and face and neck sealing marginal portions of highly extensible material, a plurality of folds in the central portion of said head covering to provide a fullness therein, a reinforcing band connecting said side portions, said marginal portions comprising a face sealing portion adapted to extend in a continuous manner across the forehead, down each side of the face and under the chin of the wearer, and a neck sealing portion adapted to extend around the neck of the wearer, the said face and neck sealing portions each having a length normally less than that required to surround the face and extend around the neck, respectively, of the wearer; whereby considerable stretching or tensioning of said highly extensible material is maintained when in position surrounding the face and extending around the neck of the wearer.

12. A substantially water-proof bathing cap construction comprising a substantially water-proof head covering including side and central panels and face and neck sealing marginal portions of highly extensible material, the rearward portion of said central panel being wider than the forward portion thereof to provide a fullness in said head covering, said marginal portions comprising a face sealing portion adapted to extend in a continuous manner across the forehead, down each side of the face and under the chin of the wearer, and a neck sealing portion adapted to extend around the neck of the wearer, the said face and neck sealing portions each having a length normally less than that required to surround the face and extend around the neck, respectively, of the wearer; whereby considerable stretching or tensioning of said highly extensible material is maintained when in position surrounding the face and extending around the neck of the wearer.

13. A substantially water-proof bathing cap construction comprising a substantially water-proof head covering, said covering having a fullness at the lower rear portion thereof to provide a snood and face and neck sealing marginal portions of highly extensible material, said marginal portions comprising a face sealing portion adapted to extend in a continuous manner across the forehead, down each side of the face and under the chin of the wearer, and a neck sealing portion adapted to extend around the neck of the wearer,

the said face and neck sealing portions each having a length normally less than that required to surround the face and extend around the neck, respectively, of the wearer; whereby considerable stretching or tensioning of said highly extensible material is maintained when in position surrounding the face and extending around the neck of the wearer.

14. A bathing cap comprising a head covering having a fullness provided by material in excess of a minimum amount required to cover the head of a wearer and provided with a face receiving aperture and a neck receiving aperture, said head covering comprising water-proof material adapted to completely house the hair and ears of the wearer and to extend about the neck, under the chin, and upwardly along the face and across the forehead of the wearer, said water-proof material being provided marginally of the neck receiving aperture and the face receiving aperture with the property of high elasticity, said margins being adapted to be maintained under tension during use whereby to effect a positive fluid seal between said margins and the body of the wearer.

15. A bathing cap comprising a head covering including side and central portions, a plurality of folds in the central portion of said head covering to provide a fullness therein, a reinforcing band connecting said side portions intermediate the front and rear portions thereof, said head covering being provided with a face receiving aperture and a neck receiving aperture, said head covering comprising water-proof material adapted to completely house the hair and ears of the wearer and to extend about the neck, under the chin, and upwardly along the face and across the forehead of the wearer, said water-proof material being provided marginally of the neck receiving aperture and the face receiving aperture with the property of high elasticity, said margins being adapted to be maintained under tension during use whereby to effect a positive fluid seal between said margins and the body of the wearer.

16. A bathing cap comprising a head covering, said covering having a fullness at the lower rear portion thereof to provide a snood and provided with a face receiving aperture and a neck receiving aperture, said head covering comprising water-proof material adapted to completely house the hair and ears of the wearer and to extend about the neck, under the chin, and upwardly along the face and across the forehead of the wearer, said water-proof material being provided marginally of the neck receiving aperture and the face receiving aperture with the property of high elasticity, said margins being adapted to be maintained under tension during use whereby to

effect a positive fluid seal between said margins and the body of the wearer.

17. For use in a substantially water-proof bathing cap construction, a substantially water-proof head covering including side and central portions, a plurality of folds in the central portion of said head covering to provide a fullness therein, and a reinforcing band connecting said side portions intermediate the front and rear portions of said side portions, with said reinforcing band serving to retain the fullness in the central portion during use.

18. For use in a substantially water-proof bathing cap construction, a substantially water-proof head covering including side and central panels, the rearward portion of said central panel being wider than the forward portion thereof by an amount which provides material considerably in excess of a minimum amount necessary to cover the head of a wearer to provide a fullness restricted to the rear portion of said head covering.

19. For use in a substantially water-proof bathing cap construction; a face and neck sealing band of highly elastic water-proof material, said band comprising a face sealing band portion adapted to extend in a continuous manner across the forehead, down each side of the face and under the chin of the wearer, and a neck sealing portion adapted to extend around the neck of the wearer; said face and neck sealing band being divided in the vicinity common to both said face sealing band portion and said neck sealing band portion, and having end portions adapted to overlie each other, one of said end portions being bifurcated to form a pair of terminal branches each having fastening means thereon, one of said terminal branches being adapted to overlie and be secured to coacting fastening means on said face sealing band portion and the other of said terminal branches being adapted to overlie and be secured to coacting fastening means on said neck sealing band portion.

CLYDE MAURICE MOORE.
